CIGARETTE VENDING MACHINE

August J. Nuss, Hollywood, Calif., assignor of
one-half to Robert C. Palmer, Whittier, Calif.

Application October 28, 1935, Serial No. 47,108

3 Claims. (Cl. 312—80)

My invention relates to a cigarette vending machine, and more specifically to a machine of that character which is adapted to deliver cigarettes only when a coin is placed within a slot in payment of the cigarettes delivered. This is the same invention for which I made application for Letters Patent on January 13, 1933, Serial No. 651,559.

The objects I have accomplished in my invention is the production of a machine of the character described which will function to deliver the cigarettes only when a coin of a predetermined denomination is placed therein, which device will at all times disclose whether there are cigarettes in the container, and adjacent to the discharge opening. A further object of the device is the fact that the operating lever can be moved before the coin is inserted for the purpose of moving the cigarettes which may be stuck within the container in a position to be delivered when the coin is inserted. Another object is the moving of the cigarettes within the container without breaking or injuring them. Other objects will be herein-after disclosed.

These objects are accomplished by means of the device hereinafter described and illustrated on the accompanying drawings in which Fig. 1 is a perspective view of the device with portions of the housing cut away for the purpose of showing mechanism within the housing. Fig. 2 is a top view of two supporting rails with portions of the mechanism supported thereby. Fig. 3 is an enlarged top view of the push rod for actuating the device. Fig. 4 is an enlarged side view of the device partly in section. Fig. 5 is a rear perspective view of the feeding device. Fig. 6 is a front view of the feeding device. Fig. 7 is a fragmentary view of the feeding device showing a fragmentary view of the agitator.

Referring to the drawings, I have provided a housing 10 in which the back portion thereof is adapted a removable lid 101. The housing may be provided with windows 11 of transparent material so that a view of the contents may be had.

Within the housing is the device constructed for the purpose of delivering the cigarettes. It consists of the following elements: Supporting rails 39 and 40 are attached to each side of the inside walls of the housing, said rails being positioned parallel with each other, and when the vending machine is positioned for operation, said rails are approximately horizontal. A plate 41 may connect said rails. The plate should have an elongated opening 22 through which the cigarettes can fall when their delivery is desired, and another opening 301 for purposes herein explained.

A cigarette dispenser 21 consists of a box frame 23 open at the top and bottom, and constructed large enough to hold one cigarette only. It is here noted that said box frame can be constructed large enough to hold a package of cigarettes, or any predetermined number, the object being that the number of cigarettes delivered from any one machine should be uniformly the same. The box frame has an extension 210 attached thereto, which extension is pivotally connected with lever 17. Lever 17 is pivotally attached to bracket 170, which bracket is rigidly attached to rail 40. The end of lever 17 adjacent to push-rod 13 is normally free. Lever 17 normally holds the box frame so that plate 41 functions as a bottom to the box frame 23, by means of a spring 171 attached to lever 17, extending lengthwise on said lever beyond the pivotal point 172, the one end of the spring being anchored to rail 40 through a bracket 174. It will be noted that normally the box frame is positioned over a portion of plate 41. When a cigarette 70 is placed within the box frame it will rest upon said plate, but by a movement of lever 17 the open box frame can be made to register with slot 22, sliding the cigarette within the box so it can drop through slot 22.

Directly under slot 22 is chute 25 which is adapted to receive a cigarette when it has dropped through slot 22. Gravity will carry the cigarette through said chute to the bottom. A discharge opening 260 is cut through the housing adjacent to the discharge end of chute 25. Outside of the housing and adjacent to opening 260 is a receiver 26 attached to said housing to receive the cigarettes when discharged from chute 25. The cigarettes in the receiver can be appropriated by the person operating the device.

The cigarettes to be dispensed are held in storage within the housing on an inclined member 28, positioned above said supporting rails 39 and 40. Said inclined member is arranged as hereinafter described so that a constant supply of cigarettes are held just above box frame 23 when the vending machine is in normal position for dispensing the cigarettes. In this position plate 41 is on an approximately horizontal plane.

To discharge the cigarettes from the box frame into chute 25, I have provided a push bar or trip 13. Push bar 13 is slidingly attached to supporting rail 39 by pins 140 and 150, which pins engage slots 14 and 15 in the push bar. The heads on pins 140 and 150 are adapted to hold the push bar adjacent to rail 39, said heads being larger in diameter than the width of the slots. The push bar is thus adapted to slide on said pins. When

assembled, push bar 13 has one end extending through slot 120 to the outside of the housing. The extended end terminates with a handle 12. The opposite end of the push bar has a peg 131 attached thereto to which one end of spring 133 is anchored. The opposing end of spring 133 is anchored to rail 39. Spring 133 normally holds push bar 13 in a position extending beyond the housing. It is noted that peg 131 extends through slot 134 in rail 39 in which slot the peg can slide back and forth with the movement of the push bar.

Guides 132 are attached to plate 41 to assist in holding the push bar within a fixed path of travel. It is also noted that the push bar is positioned at approximately right angles to lever 17.

A coin holder consisting of two slotted members 16 and 160 are attached to the push rod so the slots therein are at approximately right angles to the push rod. The slots in the two members will register when on an approximately vertical line. Slotted members 16 and 160 are positioned a spaced distance apart. The slots in said slotted members 16 and 160 are adapted to receive a coin. The space between said members, and the position of lever 17 are such that when push bar 13 is moved inward, lever 17 will pass between said slotted members, and when a coin is therein, and the push bar is moved inwardly, the coin will engage lever 17 moving it and the cigarette dispenser 21 so the cigarette therein can drop into chute 25. When push bar 13 is positioned for discharging a cigarette, the coin within slotted members 16 and 160 will be over an opening 163 in plate 41, and the coin will drop therethrough. Lever 17, and pivotally attached cigarette dispenser 21 will then be free to move to their normal positions by the action of spring 171, said spring being attached at one end to lever 17, and anchored at the other end to anchor means 174.

The limit of the movement of the cigarette dispenser is fixed by stops 19 and 220. By releasing pressure on handle 12, push lever 13 will return to normal position by the action of spring 133.

To insure delivery of cigarettes to the box form 23, I have constructed an inclined support which terminates at its lower end adjacent to said box form. The relative arrangement of the inclined support and the box frame are such that the cigarettes rolling down the incline support will roll into the box form.

A box 45 is adapted to hold a supply of cigarettes. It is constructed with an open top approximately the same width as the width of the inclined support. The ends are slightly shorter than the sides, so that when the box has cigarettes 70 therein, and box 45 is inverted on the inclined support, the cigarettes can roll through opening 450 between the end of the box and the inclined support into box frame 23 for delivery.

For the purpose of securing a constant feed of cigarettes at the lower end of the inclined support, I have invented an agitator which operates in conjunction with inclined support 28. Said support 28 is formed as a plane, and has lateral slots 47 and 48 therein. Adjacent to said slots slideways 49 and 50 are formed. These slideways are depressed below the top surface of support 28. The agitator is constructed of a channel member 54 which has outwardly extending flanges 52 and 53 on the sides of said channel member. The agitator is assembled with the inclined support so that the body portion of the agitator is 75 on the underside of said support. The sides of

the agitator extend through slots 47 and 48, and flanges 52 and 53 ride on slideways 49 and 50. The thickness of the flanges are such that when assembled the upper surface of the flanges are slightly below the upper surface of the inclined support. The relation of the slots and the sides of the agitator extending therethrough are such that the flanges can be moved so the upper surface of the flange is slightly above the upper surface of the support.

Slots 47 and 48, and slideways 49 and 50 are longer than flanges 52 and 53, so that the agitator can have a longitudinal movement on the slideways. This longitudinal movement is created by a combination consisting of a bifurcated member 55 attached to the underside of the agitator and depending downward therefrom, and a rod 30 which is attached at approximately right angles to push bar 13. When assembled rod 30 passes through the bifurcated opening in member 55. When the push bar is moved back and forth, a similar back and forth movement is transmitted to member 55, which in turn moves the agitator back and forth on the inclined support. An opening 301 in plate 41 permits the bifurcated member 55 to extend therethrough, and a rest 302 is adapted to support the free end of rod 30.

A curved leaf spring 56 has one end attached to the agitator. The other end is free. When the push bar is at rest in its normal position, the agitator will be positioned near the bottom of the slideway, and in that position spring 56 will be compressed and will hold the lower ends of flanges 52 and 53 above the upper surface of support 28, thus raising the cigarettes thereon above the plane of support 28, and the slight movement thus made will start the cigarettes rolling toward the box frame. When the agitator is moved upward, which movement is accomplished by pushing in the push bar, the tension of curved spring 56 is reduced and flanges 52 and 53 will drop down in the slideways so the top surface of the flanges will be below the top surface of support 28. A tension spring 57 holds the upper ends of the flanges constantly on the same plane, or slightly below the upper surface of the support, so by the movement back and forth of the agitator the ends of the flanges will not pierce or tear the cigarettes.

A brace 58 extending from plate 41 to support 28 is for the purpose of strengthening the assembly.

The curved members 74 and 75 shown in Fig. 6 are stops for cigarettes rolling down the inclined member 28, said stops 74 and 75 being adapted to guide the cigarettes to box form 23.

Having described my invention I claim:

1. In a device for dispensing cigarettes, said device having a housing, a chute adapted to deliver cigarettes deposited therein to the outside of the housing, a receptacle adapted to hold a supply of cigarettes, an opening in said receptacle adapted for cigarettes to be discharged therefrom, parallel longitudinal grooves in the bottom of the receptacle, said receptacle being positioned so that the bottom thereof is on an incline with the discharge opening at the lower corner thereof, and with said discharge opening adjacent to the upper end of the chute, and means for discharging cigarettes from the receptacle which discharging means is actuated by a push rod adapted to be manually operated, an agitator within the receptacle consisting of sliding members adapted normally to slide within said grooves, and being of such shapes and sizes

that they can be wholly below the plane of the upper surface of said bottom of the receptacle, means connecting the push rod with the agitator adapting the sliding members to move simultaneously with the push rod, and means for raising a portion of the sliding members slightly above the plane of the bottom of the receptacle consisting of a curved spring, one end of which is attached to the agitator, the other end being free, 10 a base, the spring being shaped so that the free end thereof is in engagement with the base when the sliding member is at the lower end of its path of travel, and is disengaged when moved upward from said lower end of its path of travel.

15 2. A device described in claim 1 hereof having yielding means adapted to constantly hold the upper end of the sliding member below the plane of the upper surface of the bottom of the receptacle.

20 3. In a device for dispensing cigarettes, said device having a housing, a chute adapted to de-

liver cigarettes deposited therein to the outside of said housing by gravity force, a receptacle adapted to hold a supply of cigarettes, an opening in said receptacle adapted for cigarettes to be discharged therefrom, said receptacle being 5 positioned so that the bottom thereof is on an incline, and so that the discharge opening therein is at the lower corner of said receptacle and adjacent to the upper end of the chute, an agitator adapted to prevent the cigarettes within the 10 receptacle from clogging the discharge opening, said agitator consisting of sliding members adapted to be moved back and forth longitudinally on the upper surface of the bottom of said receptacle, and means for raising slightly 15 said sliding member while it is sliding upward, consisting of a spring adapted to become operative as the sliding member moves upward from the lower end of its path of travel.

20 AUGUST J. NUSS.
